UNITED STATES PATENT OFFICE.

FRANK L. BARTLETT, OF PORTLAND, MAINE.

MACHINE FOR MAKING PULP CYLINDERS.

SPECIFICATION forming part of Letters Patent No. 447,455, dated March 3, 1891.

Application filed April 7, 1890. Serial No. 346,809. (No model.)

To all whom it may concern:

Be it known that I, FRANK L. BARTLETT, a citizen of the United States, residing at Portland, in the county of Cumberland and State 5 of Maine, have invented certain new and useful Improvements in Machines for Making Pulp Cylinders; and I do hereby declare the following to be a full, clear, and exact description of the invention, such as will enable 10 others skilled in the art to which it appertains to make and use the same.

My invention relates to centrifugal machines for forming cylinders of pulp or other like material.

15 The object of my invention is to overcome certain obstacles which have existed in the machines as hitherto made, particularly when applied to the manufacture of small tubes, and my invention is directed to the remedying 20 of these difficulties, as will be hereinafter pointed out.

These machines as heretofore constructed have not been automatic and have required the close attention of the operator. There 25 has also been considerable difficulty experienced in distributing the pulp uniformly throughout the length of the tube and in securing a bore of uniform and definite size each time. I correct these defects according to my 30 present invention by inserting centrally within the centrifugal cylinder a non-rotating pulp distributing or supply tube having lateral openings throughout its entire length, whereby the pulp is evenly distributed, the 35 supply automatically cut off, and the cylinder filled up solid to the core or pulp-supply pipe. Again, it has been difficult to handle tubes made on these machines when in the moist condition in which they come from the machine, and particularly when they are of any 40 considerable length, and when taken out and dried they have always had a tendency to warp or dry out of shape. I overcome this by inserting within the outer cylinder a rigid inner tube made of finely-perforated metal 45 plate. This tube is supported in such a manner as to leave a drainage-space between it and the outer cylinder. The pulp cylinders are formed, taken out, and dried in these 50 perforated tubes, of which a large number are provided for each machine. One machine is also enabled to form a great number of differ-

ent sizes by using the above-mentioned perforated sheet-metal tubes of different sizes supported within the main cylinder by rings 55 or collars of suitable size.

My invention consists of the various features which I have pointed out and other subordinate features, all of which will be clearly pointed out in the claims. 60

I have illustrated a simple form of machine embodying my invention in the accompanying drawings, in which—

Figure 1 is a central vertical longitudinal section. Fig. 2 is a section on xx of Fig. 1, 65 looking toward the right. Fig. 3 is a side elevation showing the perforated sheet-metal tube with one ring or collar in position, and Fig. 4 is a detail of cleaning-rod used in the pulp-supply pipe. 70

A is a head secured to the end of a shaft A', only a portion of which is shown, said shaft being journaled in the bearing a. The shaft A' is driven by a pulley or by any other well-known means, which it is not necessary to 75 show.

Secured to the head A is an outer cylinder B, the opposite end of which is supported in any suitable manner. As here shown, I support it in a bearing D, in which is an opening 80 to admit the end of cylinder B. Bearing-blocks d are secured to the bearing D, and these impinge against the ring c, fixed on the end of the cylinder B. A cap C closes 85 the end of the cylinder. This cap has a central opening, through which passes the pulp-supply pipe F, making a joint which is nearly or quite water-tight. This pipe extends the entire length of the machine and its inner end has a bearing f in the center of the head 90 A. In the sides of the tube F and extending throughout its entire length are numerous pulp-openings f' f', by which the pulp is evenly distributed along the cylinder. In place of separate holes I may use a longitudinal slot with good results. 95

Between the supply-tube F and the outer cylinder D is a perforated cylinder E, in which the pulp-tube is formed. This is a tube of finely-perforated sheet metal. I find tin very 100 well adapted for this purpose. This tube E is inserted into the cylinder, and is held in such a position that there will be a drainage-space between it and the outer cylinder. I

prefer to support the tube E by means of a series of rings or collars, as *e*, which are slipped on over it and are just large enough to enter the cylinder B. They may or may 5 not be soldered or otherwise fastened to the tube E. The outer end of the tube F is provided with a T-connection G, by which it is preferably connected with a pulp-supply by means of a flexible pipe *g*'. A valve *g* governs the supply of pulp. The end of the T-connection G is provided with a plug *g*², through which is an opening which admits a cleaning-rod *h*, by which the tube is kept free from obstructions. This rod *h* extends the 15 entire length of the pulp tube, and on the end of the rod *h* is an offset *i*.

The connection G is supported by a standard *g*³, which may be removably secured to the bench H in such a manner as to slide 20 longitudinally when the tube F is drawn out. A simple means is that here shown, which consists of a bolt *g*⁴, passing through a slot in the bed H, by means of which the standard *g*³ may be slid back and the supply-pipe withdrawn from the machine. A packing-ring *f*² is placed on the pipe F outside of the cap C to secure it against the chance of leaking.

The operation of the machine is as follows, 30 viz: The parts being in the position as shown in Fig. 1, the pulp is admitted through the supply-pipe and distributes itself throughout the whole length of the tube E. In practice it is found that there is no noticeable difference in thickness between what is deposited at the lower and the upper portions of 35 the tube, for as soon as the deposit reaches a certain thickness depending upon the pressure water practically ceases to pass through. If there is any difference, the tendency of the 40 pulp when rotation begins is to deposit most freely on the thin places, and thus equalize the thickness. As soon as the tube E is full of pulp the machine is rotated at full speed and the 45 pulp is deposited on the walls of the tube E, which gradually fills until the pulp reaches the supply-pipe, when it closes the holes *f*' and stops the supply. As soon as the pulp 50 formed is dried out somewhat it shrinks away from the center and admits a supply of fresh pulp through the holes *f*', and so keeps on alternately flowing and stopping until a solid tube is formed having the pipe F for a core. It will thus be seen that the action of the 55 machine is entirely automatic and requires no watching after the pulp is turned on. When the water ceases to be thrown from the pipe B, the pulp is shut off, the tube F withdrawn, the bolt *g*⁴ having previously been loosened. The cap C is then taken off, and 60 the tube E is pulled out and put away in a dry room with the pulp tube in it, until the latter is dry.

During the process of drying, the pulp will be held in shape and prevented from warping, and when dry it will shrink just enough, 65 so that it may be slipped easily from the tube.

Lest the supply-pipe become clogged, as it is liable to do, the rod *h* can be moved back and forth occasionally, so that the holes *f*' will be kept clear and free.

By means of rings *c* of suitable size I am enabled to use in a single machine having an outer cylinder of suitable size many different-sized tubes and to form many sizes of pipe—a thing which has not hitherto been 75 done on one machine. It is not important that the outer cylinder B should be perforated with numerous holes when the space between it and the tube E is considerable, as the water may be discharged through one or two 80 holes suitably located. These perforated tubes E, when made of tin, can be made cheaply, and a large number of them provided of varying sizes. It is not necessary, as I have found, to line them with wire-gauze, 85 felt, or other pervious material, the perforated metal itself being sufficient to retain and lay the pulp.

I claim—

1. In a centrifugal machine for forming 90 pulp cylinders, a rotating outer perforated tube, an inner perforated tube of smaller diameter secured concentric therewith to form a drainage-space between said tubes, and means for supplying pulp to said inner tube, 95 in combination, substantially as described.

2. In a centrifugal machine for forming pulp cylinders, an outer perforated tube, an inner perforated tube concentric therewith, and annular rings or collars for separating 100 said tubes, in combination, substantially as described.

3. In a centrifugal machine for forming pulp cylinders, a rotating pervious tube and a non-rotating pulp-supply pipe fixed centrally therein and having pulp-openings 105 throughout its entire length, in combination, substantially as described.

4. A pervious cylinder, a pulp-supply pipe extending centrally through it, a T or branch 110 at the outer end of said pipe connecting with a source of supply, a plug in the end of said pipe having an aperture therein, and a clearing-rod passing through said pipe, in combination, 115 substantially as described.

In testimony whereof I affix my signature in presence of two witnesses.

FRANK L. BARTLETT.
